UNITED STATES PATENT OFFICE.

CHAPIN C. BROOKS, OF WILTON, MAINE.

DESIGN FOR A SCYTHE.

SPECIFICATION forming part of Design No. 31,153, dated July 4, 1899.

Application filed March 8, 1899. Serial No. 708,285. Term of patent 14 years.

To all whom it may concern:

Be it known that I, CHAPIN C. BROOKS, a citizen of the United States, residing at Wilton, in the county of Franklin and State of Maine, have invented and produced a new and useful Design for Scythes; and I do hereby declare that the following is a specification thereof, reference being had to the accompanying drawings, in which—

- 10 Figure 1 is a plan of the upper side of the scythe. Fig. 2 is a vertical transverse section on the line $x-x'$ of Fig. 2.

The leading feature of my design consists in a scythe having a V-shaped rib in the web 15 parallel to the back, the convexity or point of this V-shaped rib being upward. The angle of the sides of this rib with the plane of the web is about forty-five degrees; but the

side of the rib near the back is longer than that upon the other side.

Referring to the drawings, *a* is the back of the scythe, *b* the web, and *c* the V-shaped rib. The rib is so formed that a line drawn from the cutting edge of the web upon either side of the web to the back does not intersect the rib 25 *c* nor any portion of the web except the edge.

What I claim is—

The design for a scythe as herein shown and described.

In testimony that I claim the foregoing as 30 my invention I have hereunto set my hand this 2d day of March, A. D. 1899.

CHAPIN C. BROOKS.

In presence of—

GEO. E. BIRD,
A. C. BERRY.
